UNITED STATES PATENT OFFICE.

HENRY T. ROOT, OF KIRKSVILLE, MISSOURI.

OSTEOPATHIC TABLE.

No. 848,856.

Specification of Letters Patent.

Patented April 2, 1907.

Application filed November 17, 1906. Serial No. 343,918.

To all whom it may concern:

Be it known that I, HENRY T. ROOT, a citizen of the United States, residing at Kirksville, in the county of Adair and State of Missouri, have invented a new and useful Osteopathic Table, of which the following is a specification.

This invention relates to apparatus for use by osteopaths in treating patients, and has for its principal object to provide a treating-table on which the patient may be placed and to employ in connection with the table a swinging support on which portions of the body may rest and which may be moved relatively to the table for the purpose of treating certain parts of the body, especially in the dorsal and lumbar regions.

A further object of the invention is to provide an osteopathic table with a swinging support which may be adjusted vertically with respect to the table or at any desired angle thereto and which may be readily detached when not in use.

A still further object of the invention is to provide a table of this character which may be taken apart and packed in small compass for shipment or storage.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of an osteopathic table constructed in accordance with the invention. Fig. 2 is an end view of the table, showing the bracket and the swinging support. Fig. 3 is a detail view showing the pivotal connection between the bracket and swinging arm.

Similar numerals of reference are employed to indicate corresponding parts throughout the several figures of the drawings.

The main frame of the table includes side rails 10 and end rails 11, which are connected to corner members 12, which may be formed of castings, and to the castings are secured legs 15, the lower portions of which are strengthened and braced by a tube 16, hav-

ing branched end portions 17, which are secured to the several legs by means of thumbscrews 18, so that when necessary the table may be taken apart. On top of the table is placed a mattress or cushion 19, which may be formed of any suitable material.

Secured to one of the end rails 11 is a bracket 20, which may be formed of cast-iron or other suitable material, said bracket being rigidly locked in position by a pair of bracing-rods 21, which extend from the opposite sides of the bracket to the side rails 10. This bracket carries two bearings 20^a and 20^b, vertically disposed for the support of upper and lower pintles 22, carried by a swinging arm 23. The lower bearing 20^b is open, so that the swinging arm may be readily removed from the bracket when it becomes necessary to detach said arm.

The arm may be formed of cast metal, and at its outer end is arranged a two-part clamp 24, the links of which may be forced together by means of a handled screw 25. This clamp is arranged to engage a vertically-adjustable bar 26, having a slot 27 for the passage of the screw, the construction being such that the bar may be raised or lowered or may be turned at an angle to the vertical, as desired. To the upper end of the bar 26 is secured a supporting-pad 28, on which a portion of the body of the patient may rest.

In using the device the patient is placed partly on the main table and partly on the support 28, and the latter may then be swung on its pivotal center for the purpose of treating the affected part.

The device is of especial value in the treatment of heavy patients, and more especially where the treatment is in the dorsal or lumbar regions, the device permitting the support of the main weight of the body on the table, while the lower limbs are carried by the swinging support.

I claim—

1. An osteopathic table having a bracket attached thereto, brace-rods extending from the bottom of the bracket inwardly to the sides of the table, a closed bearing and an open bearing projecting outwardly from the top and bottom respectively of said bracket, and a swinging arm provided with pintles adapted to engage said bearings.

2. An osteopathic table having a bracket attached thereto said bracket having at its top an outwardly-projecting closed bearing and at its bottom an outwardly-projecting

open bearing, and a removable swinging arm provided at one end with an adjustable rest or support and at its other end with projecting lugs adapted to extend between the bearing 5 lugs of said bracket and rest against them, said lugs having oppositely-projecting pinnacles adapted to engage said bearings.

In testimony that I claim the foregoing as my own I have hereto affixed my signature in the presence of two witnesses.

HENRY T. ROOT.
